UNITED STATES PATENT OFFICE.

WALTER O. SNELLING, OF ALLENTOWN, PENNSYLVANIA, ASSIGNOR TO TROJAN POWDER COMPANY, OF NEW YORK, N. Y., A CORPORATION OF NEW YORK.

EXPLOSIVE COMPOSITION.

No Drawing.

Application filed August 19, 1920. Serial No. 404,610.

To all whom it may concern:

Be it known that I, WALTER O. SNELLING, a citizen of the United States, residing in Allentown, Lehigh County, Pennsylvania, have invented certain Improvements in Explosive Compositions, of which the following is a specification.

My invention relates to improvements in detonating explosives, and more particularly in detonating explosives belonging to that class in which sensitiveness to detonation is noticeably decreased when the explosives are firmly packed, and to which explosives it is common practice to add wood pulp, wood flour, bran, or other equivalent light and bulky carbohydrate product for the purpose of decreasing the density of the finished explosive and to keep it from packing so firmly as to prevent detonation when loaded into cartridges under normal conditions or when pressed into a bore-hole in actual use.

While the use of wood pulp and equivalent light and fluffy materials for the purpose of decreasing the density of explosives has proved of great practical utility, there are certain classes of explosives in which such carbonaceous materials have not hitherto been successfully used. For example in the formulation of explosives for use in coal mines, it has frequently been found that the addition of wood pulp or equivalent material in quantities sufficient to bring about the desired decrease in density of the finished explosive, causes an increase in the flame temperature to an extent rendering the explosive undesirable for use in gaseous or dusty mines.

One object of this invention is to avoid the increased temperature caused by the addition of said carbonaceous materials whereby the explosives are made suitable for use in coal mining work and under conditions similar to those found in coal mines, a further object being to reduce the amount of carbon monoxide which is produced in the explosives.

I have found that if a carbohydrate material such as wood pulp, wood flour, bran, wheat middlings, or other equivalent light and fluffy product is impregnated with a substance capable of absorbing heat in the course of the explosive reaction and of retarding the combustion of carbon, the prepared product so formed may be added to an explosive composition in considerable

quantities without unduly raising the flame temperature, and that accordingly such prepared product may be used to give the desired low density to an explosive without making the explosive unsuitable for use in coal mining work.

As examples of the impregnating material which I have found suitable for the purpose of this invention, I may name such substances as sodium chloride, sodium silicate and ethane hexachloride, although there are many substances which may be used as equivalents of these materials. In order to be successfully employed, such substances should be neither combustible nor supporters of combustion, should be free of available oxygen and of substances of a combustible nature. Thus while sodium chloride and ethane hexachloride are particularly satisfactory in the application of my invention, such substances as magnesium sulfate, sodium phosphate, sodium thiosulfate and calcium chloride may be used, and in general any solid noncombustible soluble body which is free of available oxygen and which acts neither as a combustible nor as a supporter of combustion when in contact with a flame may be employed.

As an example of the preparation of a material suitable for use in connection with my present invention, I will describe the method by which I treat wood pulp for use in an ammonium nitrate explosive. I first prepare a concentrated solution of sodium chloride or equivalent substance, and thoroughly saturate my wood pulp with the solution so prepared, this saturation being accomplished by boiling; the wood pulp in the saturated solution of the sodium chloride or equivalent substance for the requisite length of time. Under normal pressures I have obtained satisfactory results in from ten to thirty minutes of boiling. After the wood pulp is thoroughly impregnated, the excess solution may be removed from the pulp in a centrifugal or in any other convenient way, the impregnated wood pulp then being dried and the finished product being a light and fluffy material thoroughly suited to the purpose for which it is employed.

This prepared fluffing agent I may use in conjunction with other normal ingredients of an explosive in quantities ranging from 1% up to 20% of the finished product.

an example of one composition which I find to give satisfactory results, the following formula is cited:

5	Nitrostarch	15.0%
	Amatol (85-15)	75.0%
	Zinc oxid	.2%
	Treated wood pulp	2.0%
	Sodium nitrate	7.8%
10		100.0%

As another example of the use of my prepared wood pulp in an explosive, and particularly for the purpose of avoiding the presence of an excessive amount of poisonous carbon monoxide in the products of combustion, the following formula may be considered:

20	Nitrostarch	25.0%
	Ammonium nitrate	10.0%
	Sodium nitrate	48.5%
	Sodium bicarbonate	.5%
	Treated wood flour	3.0%
25	Marble dust	13.0%
		100.0%

In this latter instance, the impregnation of the wood flour may be accomplished by boiling ordinary wood flour in a saturated solution of sodium thiosulfate until the wood flour is thoroughly saturated with the solution, and then removing the surplus solution by a centrifugal and drying at a low temperature.

In the course of the explosive reaction of an explosive made in accordance with the principles described above, the volatile products from the wood pulp or other material used are driven out by the intense heat generated, but the combustion of the carbon is prevented by the presence of the incombustible impregnating agent. As a result the carbon does not enter into the explosive reaction, and the flame temperature is reduced by an amount equivalent to the heat which the combustion of this amount of carbon would otherwise have yielded. Furthermore in all commercial explosives, some carbon dioxide is produced in the explosion, and if an excess of carbon is present at the moment of explosion, this excess of carbon reacts with the carbon dioxide, the carbon dioxide being reduced to carbon monoxide,

which is a very poisonous gas. Since the carbon in the carbohydrate material prepared as described is prevented from reacting chemically at the instant of explosion, it is possible by my invention to prepare explosives of relatively low density which produce gases much less objectionable and poisonous than the gases produced by other explosives containing an equivalent amount of untreated carbohydrate material. A composition similar to that of the second of the two formulas above mentioned in which ordinary wood flour is used instead of the treated, will produce an excessive amount of carbon monoxide on explosion, and the explosion gases would be dangerous to breathe, so that such an explosive could not be used in any confined place such as a mine. By the use of wood flour treated as described, an explosive of the desired density is produced, but the carbon present in the wood flour being prevented from reacting at the time of explosion, the explosion gases are relatively free from carbon monoxide.

I claim:

1. An explosive comprising a detonating agent and a carbohydrate material impregnated with a fire-resisting compound.
2. An explosive comprising a detonating agent and fibers of cellulose saturated with a non-combustible salt containing no available oxygen.
3. An explosive comprising a detonating agent, a salt containing available oxygen, and wood pulp impregnated with sodium chloride.
4. An explosive comprising nitrostarch and a carbohydrate material, impregnated with a fire resisting compound.
5. An explosive comprising nitrostarch and fibres of cellulose saturated with a non-combustible salt containing no available oxygen.
6. An explosive comprising nitrostarch, an inorganic salt containing available oxygen, and a carbohydrate material impregnated with a fire resisting compound.
7. An explosive comprising a detonating agent, a salt containing available oxygen, and wood pulp impregnated with sodium chloride.

WALTER O. SNELLING.
